SWITCH KNOB

Melvin Boldt, Chicago, Ill., assignor to Moffats, Limited, Weston, Ontario, Canada, a corporation of Ontario, Canada

Filed Dec. 7, 1964, Ser. No. 82,936

Claims priority, application Canada Oct. 22, 1964

Term of patent 7 years

(Cl. D26—13)

FIG. 1

FIG. 2

FIG. 4

FIG. 3

FIGURE 1 is a top plan view of a switch knob embodying my new design;

FIGURE 2 is a side elevation view of the device of FIGURE 1;

FIGURE 3 is a section view taken along lines 3—3 of FIGURE 2; and

FIGURE 4 is a perspective view of the switch knob of FIGURE 1.

I claim:

The ornamental design for a switch knob, as shown.
